[57] CLAIM

The ornamental design for a container for liquid shoe polish, as shown and described.

DESCRIPTION

FIG. 1 is a perspective view of a container for liquid shoe polish showing my new design;

FIG. 2 is an enlarged side elevational view thereof, the opposite side being a mirror image;

FIG. 3 is an enlarged front elevational view thereof;

FIG. 4 is an enlarged top plan view thereof;

FIG. 5 is an enlarged rear elevational view thereof;

FIG. 6 is an enlarged bottom view thereof;

FIG. 7 is an exploded perspective view thereof;

FIG. 8 is an enlarged side elevational view thereof, the opposite side being a mirror image, the closure removed for clarity of illustration;

FIG. 9 is a front elevational view of FIG. 8.
